MACHINE FOR FASTENING THE MESHES OF
MENDED KNITTED WARE

Maurice Alexandre Prodel, Bois Colombes, France

Application June 25, 1947, Serial No. 756,831
In France July 9, 1946

14 Claims. (Cl. 66—2)

1

The invention relates to a machine for fastening the meshes of knitted ware after mending chiefly in the case of meshes of mended silk, nylon or the like stockings. It is known that if one or more threads of a stocking or the like knitted ware break free fortuitously and as a consequence one or more meshes become loose, the object is generally repaired through hand mending by means of a hook or else by means of a mending machine. In both cases of hand-operated and machine-operated mending, it is necessary once the meshes have been picked up, in principle both sides of the tear to be repaired to fasten the picked up meshes, that is to pass through said meshes a thread replacing the broken thread in order to secure together the picked up meshes.

This fastening operation of the meshes is performed generally by hand and constitutes a delicate operation which it is difficult to execute in a practically invisible manner.

The invention has for its object a machine for executing mechanically in a perfect manner said fastening operation.

The principal features and advantages of the invention will appear in the following description given with reference to accompanying drawings illustrating diagrammatically and merely by way of example one form of execution of the machine for fastening the meshes. In said drawings:

Fig. 1 is a vertical cross sectional view of the machine, the cross section being executed through line I—I of Fig. 2.

Fig. 2 is a plan view of the machine already shown in Fig. 1.

Fig. 3 is a cross sectional view of this machine through line III—III of Fig. 1.

Fig. 4 is a detail view at a larger scale showing the bradawl adapted to take hold of a picked up mesh.

Fig. 5 is a cross sectional detail view at a larger scale of one of the jaw systems adapted to drive the needle.

Fig. 6 is a detail view of the needle at a larger scale.

Fig. 7 is a view illustrating the operation of the machine.

Fig. 8 is a fragmentary sectional view taken along line VIII—VIII of Fig. 2, but on an enlarged scale.

Fig. 9 is a perspective detail-view of the thread threaded in the meshes; and

Fig. 10 is a schematic elevational view of the underside of the toothed racks of Fig. 8.

Referring to the drawings, the machine in-

cludes a hollow frame 1 forming a supporting upright made of a suitable moulded material. This frame carries at a suitable point of its height a control shaft 2 provided with the driving crank 3 on the outside of the frame 1. To the shaft 2 and approximately in the middle of its length is fixed a toothed wheel 4 called hereinafter the main control wheel.

All the other members of the machine that will be disclosed hereinafter are mounted on a plate 5 secured by means of screws to the frame 1 and forming a sort of cover for said frame. As apparent from Fig. 3 said cover when secured in place forms with the horizontal an angle of about 30°. The work supporting carriage is constituted by a block 6 of triangular cross-section provided with a base 6' slidably mounted in the dovetailed groove 7 provided in the plate 5. Underneath said base 6' are provided two parallel flanges 8 and 9 spaced with reference to one another and engaging a slot 10 provided in the plate 5 in the middle of and almost throughout the length of the bottom of the groove 7. The lower surface of each of the flanges 8 and 9 is provided with teeth 11 the width *a* (Fig. 10) of which is practically equal to that of the mesh of the mended ware the meshes of which are to be fastened.

Similarly, each groove or recess, formed between the teeth 11, has a width *b* (Fig. 10) that is equal to the tooth width *a* and is thus equal to the width of a mesh. The teeth 11 of the flange 8 are staggered or off-set for the distance *c* from the teeth 11 of the flange 9; the distance *c* (Fig. 10) equals one-half the dimension of *a* or *b* and thus equals one-half of the width of a mesh.

Two symmetrical catches 12 and 13 connected together by means of a spring 14 cooperate with the teeth 11 formed on the flanges 8 and 9 respectively; said catches are pivotally secured to a stationary stud, 15 or 16 according to the case, mounted on a flange 17 secured to the lower surface of the plate 5 and lying consequently inside the frame 1. As previously pointed out, the teeth 11 on the flange 8 are off-set for a half width or half-mesh from the teeth 11 of the flange 9 in a manner such that when one of the catches 12 or 13 engages the recess formed between two teeth on a flange, the other catch is located on the projecting part of the corresponding tooth formed on the other flange.

The carriage is constantly submitted to the action of a tractive arrangement constituted by a ribbon or strip 18 secured at one end to the

block 6 and at its other end to a spring casing 19 carried by the flange 17. The catch 12 or 13 engaging the teeth of the flange 8 or 9 with which it cooperates holds the carriage fast with reference to the frame. Each catch 12 or 13 is moreover engaged by the end of a pivoting lever 20 or 21. The ends of these levers which are opposed to the ends engaging said catches project through suitable slots to the outside of the frame 1. These levers 20 and 21 have for their object to allow a disengagement and a spacing of the catches 12 or 13 with reference to the teeth on the flanges 8 and 9 whereby it is possible for the carriage to progress under the action of the spring casing 19 and on the other hand to be returned rearwardly in antagonism with the action of said spring casing.

As best shown in Fig. 8 a pivoting shutter or 25' thereof, and being provided with a slider sloping surface of the block 6 on the outside of the plate 5, said shutters being operable by the corresponding levers 24 or 25 and the shafts 24' and 25' thereof, and being provided with a slider 26 or 27 as the case may be. These shutters are adapted to position on the carriage bradawls 28 removably engaging each picked up mesh to be fastened, as shown in Fig. 8. These bradawls are formed as shown in Fig. 4 by a flat wire the width of which is substantially equal to that of a mesh or tooth 11 said wire being bent at one end that is folded back and ends with the projection 29. The latter is adapted to engage either of the two grooves 30 or 31 formed in parallelism with one another at the upper part of the triangular block 6.

The drive of the thread which is to fasten the picked up meshes is ensured through a needle 32 showing as illustrated in Fig. 6 a centrally located eye 33 and two sharp tips or points 34 and 35. This needle may be taken hold of at either end through the corresponding driving mechanism constituted by a member 36, provided with extensible jaws and housed inside a tube 37, said member being submitted to the action of a spring 38 (Fig. 5). On the inner surface of the tube 37 which tube is slidably carried in a bearing 39 rigid with the upper surface of the plate 5, is arranged a rack 40 engaging a toothed sector shown at 41 for the right hand side mechanism and at 41' for the left hand side mechanism (Fig. 3).

The sector 41 is driven by a connecting rod 42 provided with a slot 43 engaging a stud 44 rigid with a toothed wheel 45 which latter meshes with the main control wheel 4. A tweezer shaped spring 46 connects a point rigid with said connecting rod 42 with the stud 44.

Similarly the sector 41' is driven by a connecting rod 47 provided with a slot 48 engaged by a stud 49 rigid with a toothed wheel 50 identical with the wheel 45 and meshing therewith. A tweezer shaped spring 46 also connects a point rigid with the connecting rod 47 with the stud 49.

The sector 41 lies in the same plane as the catch 12 and the sector 41' lies in the same plane as the catch 13, each of said sectors being adapted to act on the tail end 51 or 52 forming an extension of the corresponding catch 12 or 13.

If a, b, and c and a', b', c' (Fig. 7) designate the meshes picked up on a knitted ware such as a stocking and if it is desired to fasten said meshes by means of a thread f passing through said meshes, the fastening operation is obtained as follows, taking into account that as the mending is proceeded with, the last loop is held fast by means of a bradawl 28 whereby at the moment of

fastening the picked up meshes the latter may be each provided with its bradawl.

The bradawls corresponding to the meshes a, b, c, and those corresponding to the meshes a', b', c' are arranged on the carriage in a manner such that the tips of the bradawls corresponding to the former meshes may lie for instance in the groove 30 and those of the bradawls corresponding to the latter meshes in the groove 31. The bradawls of each face of the carriage 6 are held fast through pressure of the covers 22 and 23 and are pressed against one another by the sliders 26 and 27. It should be noticed that in this position the bradawls lying in one of said grooves lie one-half breadth or one-half mesh ahead of those lying in the other groove, the stocking B being held vertically substantially as shown in Figs. 3 and 8. The staggered or off-set positioning of the bradawls 28 of one face of the carriage 6 relative to those of the opposite face, for a one-half mesh width, is brought about by the provision of stops at the left end (Figs. 1 and 2) of the carriage towards which the bradawls are pressed in the direction D by means of the mutually operated sliders 26 and 27, which stops (not shown) project towards the right for distances differing by a one-half mesh distance.

When the machine starts, the carriage is located with reference to the needle 32 in a manner such that said needle may pass through the meshes a and a' held fast by the two first bradawls. To make the thread f pass through the different meshes it is simply necessary to rotate the crank 3.

The rotation of the crank 3 will cause the sector 41 (in the position shown in Fig. 3) to move the right hand tube, that is controlled thereby, to the right in the direction A. Simultaneously, the sector 41' will tend to move the left hand tube 37 thereof also to the right. While the right hand tube 37 will move in its entirety to the right, the left hand tube, though, will move to the right only with one part and for a certain distance, but the remaining part consisting of a shoulder, a screw carried thereby, and the expansion jaw 36 thereof, will be prevented from moving, and this will cause the jaw to open and to release the needle 32 that was held therein at its end portion 34.

The rightward movement of the right hand tube 37 will release the jaw mechanism thereof and will cause the end portion 35 of the needle 32 to be gripped by the jaw under the impulse of the spring 38. During the rightward movement, the needle is passed through the meshes a' and a (corresponding to an upward movement in direction A in Fig. 7) and thus the thread f, that is carried in the eye 33 of the needle 32, is passed through these meshes (see also Fig. 8).

At the end of the rightward stroke of the right hand tube 37, the sector 41 will release the catch 12 by actuating the tail end 52 of said catch 12 with the notch of said sector 41, thereby rocking said catch 12 counter-clockwise (Fig. 3) and disengaging the catch from the rack 11 of the flange 8. This release will enable the spring powered ribbon 18 to move the carriage 6 in a direction towards the axis of the aligned tubes 37 (direction D—Fig. 2), for a distance corresponding to c (Fig. 10) which is one-half of the width of a mesh; after the carriage 6 has moved for that distance, the catch 13 which has been disposed on the exterior of the teeth of the flange 8 will drop into the next groove of the rack 11

thereof, under the impulse of the spring 14 thus temporarily blocking further movement of the carriage in direction D under power of the ribbon 18 and holding the carriage in temporary fixed position.

Continued rotation of the crank 3 will bring about a reversal of the direction of movement of the sector 41, causing the latter to return the right hand tube 37 to its initial position, by moving it leftwards in direction C. At the end of the leftward stroke of the right hand tube in its entirety, the needle 32 will be released by the jaws and be passed to the opposite tube, thereby moving the thread *f* through the meshes *b* and *a* (corresponding to a downward direction C in Fig. 7). Substantially at the instant of needle release by the right hand tube, the left hand tube will start on its leftward stroke operated by the sector 41.

The entire operation, as disclosed in the foregoing for the right hand side of the machine, will now take place on the left side thereof, until the needle 32 is again returned to the right hand tube, subsequent to a movement of the carriage 6 for a one-half mesh width step in the direction D. The entire operation may then be repeated as often as desired. The rightward and leftward movements of the tubes 37 are controlled by the positioning of the studs 44 and 49 relative to each other on the gears 45 and 50. The movement of these studs is translated to the sectors 41 and 41', respectively, by the connecting rods 42 and 47, each of them being connected to the studs by means of an elastic medium, namely, a tweezer spring 46.

When all the picked up meshes have received the thread *f* and possibly one or two of the meshes located to either side of the picked up meshes have also received it, the operation consisting in fastening the meshes is at an end and it is merely necessary to remove the mended ware from the carriage together with the Bradawl and to cut the thread *f*.

To return the carriage to its starting point for the beginning of a further operation, it is sufficient to depress the projecting ends of the levers 20-21 associated with the catches 12 and 13 and to draw the carriage in a direction opposed to the action of the spring-case 19.

It is thus apparent that the machine described hereinabove provides for a fastening of the picked up meshes in a mechanical accurate manner. Consequently a knitted ware, such as a stocking shows practically when mended no trace of repair. It should be noted that with the machine illustrated, the knitted ware such as a stocking rests through its right side on the work supporting carriage whereby the work is executed on the inside of the stocking.

Obviously, the machine described hereinabove is to be considered solely as an exemplification intended to allow an easier explanation of my invention without any binding sense and many detail modifications may be brought to the form of execution disclosed without widening thereby the scope of my invention as defined in accompanying claims. Thus for instance, it is possible to replace the control through a crank by a mechanical, electrical, pneumatic or the like control. Similarly the driving means provided for the needle may be different from those disclosed hereinabove.

What I claim is:

1. A machine for fastening the meshes of mended knitted ware comprising a work support-

ing carriage, means for intermittently causing said carriage to advance through a length corresponding to one-half mesh of the ware and a needle adapted to move reciprocatingly in a direction perpendicular to the direction of progress of the carriage and to pass the fastening thread through the mended meshes.

5 2. A machine for fastening the meshes of mended knitted ware comprising a work supporting carriage, means for intermittently causing said carriage to advance through a length corresponding to one-half mesh of the ware, a needle including a central eye and two terminal sharp tips adapted to move reciprocatingly in a direction perpendicular to the direction of progress of the carriage and to pass the fastening thread through the mended meshes and jaw members located to either side of the needle and adapted to move perpendicularly to the movement of progress of the carriage and to take hold alternately of the sharp tips of the needle.

10 3. A machine for fastening the meshes of mended knitted ware comprising a work supporting carriage of triangular cross section, a support over which said carriage is slidingly secured, means for urging continuously the carriage forward and double means for engaging the carriage alternately for constraining it to move through a succession of steps each one of which is equal to one-half mesh of the ware and a needle adapted to move reciprocatingly in a direction perpendicular to the direction of progress of the carriage and to pass the fastening thread through the mended meshes.

15 30 35 4. A machine for fastening the meshes of mended knitted ware comprising a work supporting carriage of triangular cross section, a support over which said carriage is slidingly secured, means for urging continuously the carriage forward, two racks arranged longitudinally on the surface of the carriage that is not in contact with the knitted ware, two pivoting catches adapted to engage in alternation the two racks, the two racks comprising teeth spaced by intervals equal to one mesh of the ware and the teeth of each rack off-set for a distance of one-half tooth width from the teeth of the other rack, a needle adapted to move reciprocatingly in a direction perpendicular to the direction of progress of the carriage and to pass the fastening thread through the mended meshes.

20 40 45 50 55 60 65 70 75 5. A machine for fastening the meshes of mended knitted ware comprising a work supporting carriage of triangular cross section, a support over which said carriage is slidingly secured, means for urging continuously the carriage forward; two racks arranged longitudinally on the surface of the carriage that is not in contact with the knitted ware, two pivoting catches adapted to engage in alternation the two racks, the two racks comprising teeth spaced by intervals equal to one mesh of the ware and the teeth of each rack off-set for a distance of one-half tooth width from the teeth of the other rack, a spring connecting the two catches together for urging them into their operative positions and a needle adapted to move reciprocatingly in a direction perpendicular to the direction of progress of the carriage and to pass the fastening thread through the mended meshes.

6. A machine for fastening the meshes of mended knitted ware comprising a work supporting carriage of triangular cross section, a support over which said carriage is slidingly secured, means for urging continuously the carriage for-

ward, two racks arranged longitudinally on the surface of the carriage that is not in contact with the knitted ware, two pivoting catches adapted to engage in alternation the two racks, the two racks comprising teeth spaced by intervals equal to one mesh of the ware and the teeth of each rack offset for a distance of one-half tooth width from the teeth of the other rack, a spring connecting the two catches together for urging them into their operative positions, pivoting members adapted to act on the corresponding catches for releasing them with reference to the corresponding rack teeth and controlled from the outside of the machine and a needle adapted to move reciprocatingly in a direction perpendicular to the direction of progress of the carriage and to pass the fastening thread through the mended meshes.

7. A machine for fastening the meshes of mended knitted ware comprising a work supporting carriage, a stationary spring case the spring of which is adapted to drive said carriage constantly forwards, means for transforming said drive into an intermittent progression through half mesh distances and a needle adapted to move reciprocatingly in a direction perpendicular to the directional progress of the carriage and to pass the fastening thread through the mended meshes.

8. A machine for fastening the meshes of mended knitted ware comprising a work supporting carriage provided with two parallel grooves to either side of its longitudinal axis, bradawls adapted to engage the last loops of the mended meshes and engaging the corresponding groove, means for intermittently causing said carriage to advance through a length corresponding to one-half mesh of the ware and a needle adapted to move reciprocatingly in a direction perpendicular to the direction of progress of the carriage and to pass the fastening thread through the mended meshes, said meshes being held by the corresponding bradawls.

9. A machine for fastening the meshes of mended knitted ware comprising a work supporting carriage provided with two parallel grooves to either side of its longitudinal axis, bradawls adapted to engage the last loops of the mended meshes and engaging the corresponding groove, pivoting shutters adapted to urge the bradawls against the carriage, sliders urging the bradawls cooperating with one groove of the carriage against one another, means for intermittently causing said carriage to advance through a length corresponding to one-half mesh of the ware and a needle adapted to move reciprocatingly in a direction perpendicular to the direction of progress of the carriage and to pass the fastening thread through the mended meshes, said meshes being held by the corresponding bradawls.

10. A machine for fastening the meshes of mended knitted ware comprising a work supporting carriage provided with two parallel grooves to either side of its longitudinal axis, bradawls adapted to engage the last loops of the mended meshes and engaging the corresponding groove, said bradawls being constituted by a flat bent wire forming a terminal projection and the width of which is substantially equal to that of the mesh to be fastened, means for intermittently causing said carriage to advance through a length corresponding to one-half mesh of the ware and a needle adapted to move reciprocatingly in a direction perpendicular to the direction of progress of the carriage and to pass the fastening

thread through the mended meshes, said meshes being held by the corresponding bradawls.

11. A machine for fastening the meshes of mended knitted ware comprising a work supporting carriage provided with two parallel grooves to either side of its longitudinal axis, bradawls adapted to engage the last loops of the mended meshes and engaging the corresponding groove, pivoting shutters adapted to urge the bradawls against the carriage, sliders urging the bradawls cooperating with one groove of the carriage against one another, the bradawls cooperating with one carriage groove being off-set for one-half their breadth with reference to those of the other carriage groove, means for intermittently causing said carriage to advance through a length corresponding to one-half mesh of the ware and a needle adapted to move reciprocatingly in a direction perpendicular to the direction of progress of the carriage and to pass the fastening thread through the mended meshes, said meshes being held by the corresponding bradawls.

12. A machine for fastening the meshes of mended knitted ware comprising a work supporting carriage, means for intermittently causing said carriage to advance through a length corresponding to one-half mesh of the ware, a needle including a central eye and two terminal sharp tips adapted to move reciprocatingly in a direction perpendicular to the direction of progress of the carriage and to pass the fastening thread through the mended meshes, jaw members located to either side of the needle and adapted to move perpendicularly to the movement of progress of the carriage and to take hold alternately of the sharp tips of the needle, tubular members provided with rack teeth on their outside and inside which is fitted the corresponding jaw member, a toothed sector meshing with each last mentioned rack, a central driving pinion, gear wheels driven by the latter and connecting rods operatively connecting the gear wheels with the toothed sectors.

13. A machine for fastening the meshes of mended knitted ware comprising a work supporting carriage, means for intermittently causing said carriage to advance through a length corresponding to one-half mesh of the ware, a needle including a central eye and two terminal sharp tips adapted to move reciprocatingly in a direction perpendicular to the direction of progress of the carriage and to pass the fastening thread through the mended meshes, jaw members located to either side of the needle and adapted to move perpendicularly to the movement of progress of the carriage and to take hold alternately of the sharp tips of the needle, tubular members provided with rack teeth on their outside and inside which is fitted the corresponding jaw member, a toothed sector meshing with each last mentioned rack, a central driving pinion, gear wheels driven by the latter, a slotted connecting rod pivotally secured to each toothed sector, a stud rigid with each gear wheel engaging the slot of the corresponding connecting rod and a spring member connecting the connecting rod with the wheel stud.

14. A machine for fastening the meshes of mended knitted ware comprising a work supporting carriage, means for intermittently causing said carriage to advance through a length corresponding to one-half mesh of the ware including means for urging continuously the carriage forward, two racks arranged longitudinally on

the surface of the carriage that is not in contact with the knitted ware, two pivoting catches adapted to engage in alternation the two racks, the two racks comprising teeth spaced by intervals equal to one mesh of a ware and the teeth of each rack off-set for a distance of one-half tooth width from the teeth of the other rack, a needle including a central eye and two terminal sharp tips adapted to move reciprocatingly in a direction perpendicular to the direction of progress of the carriage and to pass the fastening thread through the mended meshes, jaw members located to either side of the needle and adapted to move perpendicularly to the movement of progress of the carriage and to take hold alternately of the sharp tips of the needle, tubular members provided with rack teeth on their outside and inside which is fitted the corresponding jaw member, a toothed sector meshing with last mentioned rack teeth on the corresponding tubu- 20

lar member, a central driving pinion, gear wheels driven by the latter, connecting rods operatively connecting the gear wheels with the toothed sectors and means whereby by each toothed sector controls at each cycle of operation the corresponding catch for releasing it with reference to the cooperating rack teeth.
